UNITED STATES PATENT OFFICE.

JACOB D. DE LANGE, OF RAYMOND, MINNESOTA.

CUSPIDOR HOLDER AND CLEANER.

No. 828,275.

Specification of Letters Patent.

Patented Aug. 7, 1906.

Application filed October 16, 1905. Serial No. 282,939.

To all whom it may concern:

Be it known that I, JACOB D. DE LANGE, a citizen of the United States, residing at Raymond, in the county of Kandiyohi and State of Minnesota, have invented certain new and useful Improvements in Cuspidor Holders and Cleaners, of which the following is a specification.

My invention relates to improvements in cuspidor holders and cleaners; and it consists in the features of construction, combination, and arrangement of parts hereinafter described and claimed.

In the accompanying drawings, forming part of this specification, Figure 1 is a front elevation of my device shown in use with a cuspidor of usual type. Fig. 2 is a rear elevation of the same in cleaning position, the cuspidor being shown in section. Fig. 3 is a side elevation showing the cuspidor turned into emptying position. Fig. 4 is a section upon line $x-x$ of Fig. 1, and Figs. 5 and 6 are details of part of the construction.

As shown in the drawings, the device comprises tongs 2, having pivotal connection 3 and provided at one end with handles 4. Having pivotal support 5 in the free ends of the tongs are arms 6, having each a curved inner end 7, shaped to fit the neck of the cuspidor 8. Upon the outer end of one of the arms 6 is a handle 9, by which the arm may be turned upon its pivot, and with it the cuspidor, as shown in Fig. 3. The curved end of each arm has, preferably, a cushion 10, of leather or other yielding material.

Carried by the pivot 3 of the tongs is a sleeve 11, in which is slidably supported a rod 12, having at its upper end a handle 13 and at its lower end a cleaner 14. Having sliding support upon the rod above the cleaner is a cross-bar 15, which has a squared opening 16, through which passes the squared lower end of the rod 12. The cross-bar is held in adjusted position by means of a spring 17, secured to the cross-bar and bent to bear against the rod 12, as shown in Fig. 5. Secured to the cross-bar 15 are depending cleaners 18. The cleaners 14 and 18 may be made of loosely-connected wire rings, as shown, or may be brushes or other suitable cleaning devices. The cross-bar is bent upwardly from the rod 12, as shown in Fig. 2, to bring the cleaners 18 against the rim of the cuspidor.

In operation the tongs are manipulated to

bring the curved ends of the arms 6 against the neck of the cuspidor, as shown in Fig. 1, so that the operator by pressing together the handles 4 can hold the cuspidor firmly and carry it to any desired place. To empty the cuspidor after it has been raised by means of the tong-handles 4, it is only necessary to turn the handle 9, which will revolve its connected arm 6, this arm carrying with it the cuspidor and the opposite arm 6, as shown in Fig. 3. When the cuspidor has been returned to the position shown in Fig. 1, it may be cleaned by turning the rod 12 with its sleeve 11 into upright position and sliding the rod down to bring the cleaning devices into the cuspidor, as shown in Fig. 2. When the rod is lowered, it will bring the cleaner 14 into position to clean the bowl of the cuspidor and the cleaner 18 into position to clean the cuspidor-rim. If the cross-bar is too low upon the rod, its descent will be stopped by engagement with the top of the cuspidor, so that the cleaner 18 will always be in position to clean the rim or flange no matter how deep may be the bowl. This result is accomplished by having the cross-bar slideable upon the rod. When the rod and cleaners are in the position shown in Fig. 2, the rod may be revolved by means of its handle 13. The cleaners in their revolution will thoroughly clean the inside of the cuspidor.

Having now described my invention, what I claim as new, and desire to secure by Letters Patent, is—

1. An apparatus of the class described comprising a pair of pivotally-connected tongs, transversely-pivoted arms in the free ends of said tongs, an actuating-handle for said arms, a cleaning device slidably supported by said tongs, and an actuating-handle for said device.

2. A cuspidor-cleaning device of the class described, comprising a pair of pivotally-connected tongs, transverse supporting-arms pivoted in the free ends of said tongs, an actuating-handle for said arms, a rod having slidable rotatable support upon said tongs, and cleaning devices carried by one end of said rod.

3. A cuspidor-cleaning apparatus of the class described comprising a pair of pivotally-connected tongs, transverse arms pivotally supported in the free ends of said tongs, an actuating-handle for said arms, a sleeve rotatably supported upon said tongs, a rod

slidable in said sleeve, a handle upon one end of said rod, and cleaning devices carried by its other end.

4. A cuspidor-cleaning apparatus of the class described comprising a pair of pivotally-connected tongs, pivoted supporting-arms carried by the free end of said tongs, an actuating-handle for said arms, a rod having rotatable slidable support upon said tongs, a handle carried by one end of said rod, and cleaning devices slidably supported upon the other end of said rod.

5. A cuspidor-cleaning apparatus of the class described comprising in combination a pair of pivotally-connected tongs, transverse

rotatable supporting-arms carried by the free end of said tongs, an actuating-handle for said arms, a sleeve rotatably supported upon said tongs, a rod slidable within said sleeve, a handle carried by one end of said rod, a transverse bar having slidable spring-support upon the opposite end of said rod, and cleaning devices carried by said bar and the adjacent portion of said rod.

In testimony whereof I affix my signature in presence of two witnesses.

JACOB D. DE LANGE.
